CLAIM

The ornamental design for a wireless access point for inter-communication voice system, as shown and described.

DESCRIPTION

FIG. 1 is a front prospective view of a wireless access point for intercommunication voice system showing my new design;

FIG. 2 is a side view thereof;

FIG. 3 is a top view thereof;

FIG. 4 is a front view thereof;

FIG. 5 is a side elevation of the side opposite that shown in FIG. 2;

FIG. 6 is a bottom plan view; and,

FIG. 7 is a side elevation of the side opposite that shown in FIG. 7.

The broken lines shown in the drawings represent environmental structure and form no part of the claimed ornamental design claimed.
